UNITED STATES PATENT OFFICE

SIDNEY E. ANDERSON, OF MAPLEWOOD, NEW JERSEY, ASSIGNOR TO WESTERN ELECTRIC COMPANY, INCORPORATED, OF NEW YORK, N. Y., A CORPORATION OF NEW YORK

VACUUM TUBE CIRCUITS

Application filed December 24, 1928, Serial No. 682,418. Renewed March 16, 1929.

The present invention relates to wave reception, and particularly to the reception of high frequency waves, such as radio waves. The invention has special application to radio frequency amplifiers.

It is an object of the invention to secure uniform and high amplification over a wide range of wave lengths in the relatively short wave length region.

10 A radio receiving circuit is disclosed in application, Serial No. 654,990 of Dana A. Griffin, filed August 1, 1928, in which the first stage of the radio frequency amplifier comprises two vacuum tubes connected in 15 push-pull of parallel-opposed relation with respect to the incoming circuit and in which subsequent stages each comprises a single vacuum tube amplifier. Among the advantages of this type of circuit are that the 20 singing tendency is reduced and that the wave length range over which substantially uniform amplification is obtained is considerably increased over the case where a single tube is used in each stage. This latter effect is secured by providing individual 25 couplings, such as transformers, between the respective tubes of the push-pull circuit and the succeeding stage and by designing these 30 transformers so that they have different and overlapping frequency transmission characteristics. Further, when the circuit is provided with connections for enabling the 35 tubes to serve both as radio or audio frequency amplifiers, after the manner of the so-called reflex circuit, the first stage of the 40 radio frequency amplifier may advantageously be used as the final stage for the audio frequency amplification, and by virtue of the push-pull connection, the circuit is capable of carrying a large audio frequency load without impairing the quality.

A more specific object of the present invention is to provide an improved radio receiving circuit of the general type disclosed in the Griffin application referred to.

45 A feature of the invention comprises circuit provisions for enabling the advantages pointed out above in connection with the circuit of Griffin's application to be realized 50 in a radio receiver in which the filaments

or cathodes of the various vacuum tubes are included serially in the filament heating circuit rather than in parallel.

A further feature comprises an improved 55 form of inter-stage coupling between the initial or push-pull stage and the succeeding stages to secure a more uniform transmission throughout a wide wave length range. Specifically, this latter feature comprises a three-winding transformer and a particular 60 manner of connecting the windings of this transformer in the circuit to secure the most efficient results in accordance with applicant's discovery.

An incidental feature comprises the manner 65 of connecting the wave intercepting circuit with the initial amplifier stage.

The exact nature of the invention and the 70 various objects and features will appear more fully from the following detailed description of the invention as embodied in typical radio receiving circuits shown in the drawing.

75 Fig. 1 is a schematic circuit diagram of a radio receiving circuit of one form which the invention may take; Fig. 1A shows a type of loop antenna suitable for use with the invention; Fig. 2 is a schematic circuit diagram of a radio receiver, in which provision is made for employing the same tubes 80 for radio and audio frequency amplification after the manner of the so-called reflex circuit; Fig. 3 shows a modified circuit arrangement which may be adopted for the initial stage of the radio frequency amplifier 85 and the final stage of the audio frequency amplifier; Figs. 4 and 5 illustrate different modes of connection of the transformer windings between the push-pull stage and the 90 succeeding stage; Fig. 6 is a view in section of one form which the three-winding inter-stage transformer may take; and Fig. 95 7 shows curves illustrative of the effects of the different manners of connection illustrated in Figs. 4 and 5.

100 Referring first to Fig. 1, the receiving antenna 10 is provided with the usual tuning condenser and with the inductance 11, which may be coupled, preferably variably, with the secondary inductances 12 and 13.

When the switches 14 and 15 are closed, the secondary tuning condenser 15' is connected across the secondaries 12 and 13, these having interposed between them the fixed condensers 16, which are preferably of large enough capacity not to influence the tuning of the secondary circuit to any great extent. The outer terminals of the secondaries 12 and 13 are connected to the grids of the respective vacuum tubes 17 and 18, which may be of the well known three-element type including a cathode, an anode and a suitable type of control element, such as the grid. These tubes 17 and 18 are connected in parallel-opposed or push-pull relation with respect to the incoming circuit 10, 11 and serve to amplify the received radio frequency waves. The tubes 17 and 18 have included in their respective anode circuits individual primary windings 19 and 20, respectively, both of which are coupled to the common secondary 21 in the grid circuit of the second stage amplifier 22. Any number of succeeding stages of radio frequency amplification may be employed in addition to the amplifier 22. For the sake of simplicity, however, only one such succeeding stage is shown, this being coupled to the detector 23 by means of a second radio frequency transformer 24. The detector 23 is provided with the usual grid leak and condenser arrangement shown, and includes in its output circuit a receiver R of any suitable type, such as a head set or a loud speaking receiver. Space current is supplied to all of the tubes from the common source 28.

The filamentary cathodes of all of the tubes are connected in series with each other and the filament heating source 25, the negative pole of which is connected to earth. This heating circuit may be traced from the grounded pole of battery 25, first through the filament of the detector 23, then through the filament of the second stage amplifier 22, then through the filament of the tube 17, and finally through the filament of the tube 18 to the positive pole of the battery 25.

In order that the tubes 17 and 18 may operate properly in a balanced amplifier circuit, it is necessary that the grid of each tube have the proper normal potential relations with its own filament, and in general, the same potential with respect to its filament. The proper grid polarization for these tubes is obtained in accordance with the invention by connecting the grids to the proper points in the series filament heating circuit. For example, it will be seen that the grid of the tube 17 is connected to the more negative terminal of the filament of tube 22, which filament is included in the series filament heating circuit, next to the filament of the tube 17 in the direction of the negative pole of the filament heating

battery. The grid of the tube 17 is therefore polarized more negative than the negative end of its cathode by the amount of potential drop in the filament of tube 22. Similarly, the grid of the tube 18 is connected to the more negative end of the filament of tube 17, which filament is included between the negative pole of battery 25 and the filament of tube 18 and is next adjacent the filament of tube 18 in the filament heating circuit. The grid of the tube 18 therefore possesses a polarizing potential which is more negative than the negative end of its own filament by the amount of the potential drop through the filament of the tube 17. Since tubes may readily be selected which have substantially the same filament resistance, the polarization of the grids of tubes 17 and 18 may, by the circuit arrangement just described, be made for all practical purposes equal.

The grid of the amplifier 22 may in a similar manner be polarized more negatively than its own filament by connecting it, as shown, to the more negative end of the filament of tube 23.

This mode of connection of the filaments in series is of particular advantage in the case of tubes using low voltage filaments, such as the well known "dry cell" tubes. Such tubes require only small energy to heat the filaments. It is advantageous to connect their filaments in series since dry cells do not operate well in parallel on account of their having different characteristics.

When the series type of filament heating circuit is to be used, a difficulty arises in the manner of impressing the received waves upon the grids of the push-pull tubes and of tuning the grid circuits of these tubes to the wave length to be received. In the case where the filaments are connected in parallel, as in the Griffin application above referred to, the filaments of the push-pull tubes are at the same potential, and a connection may therefore be made from the common filament circuit of these tubes to the mid-point of the secondary of the input transformer. When the series filament heating circuit is employed, however, independent conductive circuits must be maintained between each grid and a different point of the filament heating circuit so that a different mode of impressing the waves on the grids must be adopted. In accordance with the invention, individual alternating current paths are provided from each grid through one or the other of the secondary inductances 12 or 13 and one or the other of the condensers 16 to a common point in the circuit, such as ground. Since the cathodes are also connected to ground, the alternating current potentials impressed on the two grids may be made equal by this form of connection.

In order to make use of the push-pull circuit to secure a broader characteristic for the amplifier, it is necessary, as pointed out above, to provide transmission paths between the individual tubes 17 and 18 and the second stage tube 22, which paths have respectively different transmission characteristics. This may be done, as in the Griffin application referred to, by providing two separate transformers between these two stages. It has been found, however, in practice, that in some cases the use of two separate transformers introduce difficulties, the causes of which are not thoroughly understood, but which may be due to different phase relations existing between the waves in the two transformers so that in one region of the wave length range a different resultant effect is obtained from that which exists in a different region of the wave length range. Such difficulties have been overcome in accordance with the invention by providing a three-winding transformer comprising the primary windings 19 and 20 and the common secondary winding 21.

The manner of constructing this transformer is best illustrated in Fig. 6, to which reference will now be made. The spool 26, preferably of insulating material, has cut into it three parallel, concentric, annular grooves, in which the windings are placed. These grooves have relatively great depth compared with their width. In one instance, the spool had an external diameter of the order of 2 inches, each groove was of the order of $\frac{1}{2}$ inch deep and of $\frac{1}{16}$ of an inch, or preferably less, in width. No attempt has been made in Fig. 6 to employ a scale to denote the preferred relative dimensions. In Fig. 6, the preferred positions of the windings 19, 20 and 21 are indicated. The spacing between the respective windings and the number of turns in each winding may be varied depending on the wave lengths to be transmitted, the design of the tube used, etc., and in general it will be found that by using a different number of turns in the two windings 19 and 20 and by properly relating these windings to the common secondary 21, the amplifier will be given a much broader wave length characteristic than as though the windings 19 and 20 had each the same number of turns. The proper number of turns to be used in an initial case may be determined by a cut-and-try method, and it will in general be readily observed whether a given change in the number of turns improves the characteristic in the desired direction or not, so that by a few successive tries, with the previous knowledge that the number of turns in the windings 19 and 20 should be different, will secure the desired transmission characteristic.

It has been found that the transmission characteristic depends not only upon the

dimensions of the three-winding transformer, both the mechanical and electrical, but also upon the manner of connecting it into the circuit.

The effect of the different modes of connection is shown in Figs. 4, 5 and 7. In Fig. 4, the anode of the tube 17 is connected to the outer terminal of the winding 19, this terminal being indicated in Figs. 4 and 6 as α . The anode of the tube 18 is connected to the inner terminal of the winding 20, this being indicated in Figs. 4 and 6 by β . The other terminals of the windings 19 and 20 are connected together and through the plate battery to the filament circuit. The inner terminal of the winding 21 is connected to the grid of the tube 22 and the outer terminal is connected to the filament circuit. With this type of connection it is found that a characteristic of relatively narrow wave length range and with the highest amplification at the central portion only is obtained. This is indicated by the curve I of Fig. 7. It is, of course, immaterial whether the plate of the tube 17 is connected to the outer terminal of the winding 19 or whether the plate of the tube 18 is connected to the outer terminal of the winding 20 so long as the plates of the respective tubes are connected to respectively opposite terminals, that is, one to the outer and the other to the inner. It is also immaterial whether the grid of the tube 22 is connected to the inner or the outer terminal. So long as the plates of the tubes 17 and 18 are connected to respectively opposite terminals of the primary windings, a characteristic of the general form shown by curve I of Fig. 7 is obtained.

By reversing the connections of one of the primary windings, however, as in Fig. 5, so that the anodes of both tubes 17 and 18 are connected to the analogous terminals of the windings 19 and 20, a broad characteristic, such as is shown by the curve II of Fig. 7, is obtained. No explanation of this effect is attempted here except that it is probably due to the capacity relations between the different windings, it being known that at the relatively short wave lengths the capacity effects between different portions of the circuit have considerable influence on the transmission characteristics.

In reversing the terminal connections of a winding in this manner, it is of course necessary that the direction of the winding itself be also reversed to avoid the output of one of the tubes 17 opposing that of the other tube in its effect in transmitting waves to the common secondary.

The transformer 24 preferably has a wave-length gain characteristic such that it cooperates with the transformer 19, 20, 21 to give substantially uniform transmission over a wave-length range as broad as the characteristic of the transformer 19, 20, 21 alone.

This may result, for example, from the transformer 24 having its highest gain displaced in the wave-length range from the point or points of highest gain of amplifier 19, 20, 21 so that the combined effect of the two transformers in giving uniform transmission is superior to either alone.

The circuit of Fig. 1 employs an open antenna 10, 11. If it be desired to use a loop antenna, the switches 14 and 15 are opened and the double loop shown in Fig. 1A is connected to the receiving circuit at the terminals *a*, *b*, *c* and *d*, respectively. With this manner of connection the individual inductances 12 and 13 are replaced in the circuit by the individual loops.

Fig. 2 illustrates a circuit of the same general type as that shown in Fig. 1, the main difference being that in Fig. 2 additional elements are provided for enabling the radio frequency amplifier tubes to serve also for audio frequency amplification. This is accomplished by including in the output of the detector tube 23, the primary of an audio frequency transformer, the secondary of which is included in the grid circuit of the tube 22 so that the detected audio frequency waves are impressed upon the tube 22 for amplification. The amplified audio frequency waves from the tube 22 pass into the primary windings of the audio frequency transformer 31, the secondaries of which are included in the respective grid circuits of the tubes 17 and 18. The manner of connection is such that the tubes 17 and 18 serve as a balance or push-pull amplifier for the audio frequency waves, the amplified waves appearing in the primary of the output transformer 32 leading to the receiver *R* of any suitable type. The various audio frequency transformers are preferably provided with small radio frequency by-pass condensers in accordance with the usual practice.

A somewhat simplified alternative type of connection is shown in Fig. 3. This figure shows only so much of a radio receiving circuit as lies to the left of the broken line *B*—*B* of Fig. 2, it being assumed that the portion of Fig. 2 lying to the right of this line is to be added to the circuit of Fig. 3 to the right of the line *B*'—*B*'. In the modified circuit arrangement of Fig. 3, the filaments of the tubes 17' and 18' are connected in parallel with each other, and this parallel combination is included in series in the filament heating circuit for the remainder of the filaments. This permits a somewhat simpler input connection for both the radio and the audio frequency waves for the tubes 17' and 18'. In Fig. 3, it is assumed that the audio frequency waves are impressed upon the tubes 17' and 18' in parallel rather than in parallel-opposed or push-pull relation. For this purpose the second-

ary of the audio frequency transformer 31' is included serially in the common branch of the tubes 17' and 18', it being remembered that the conductor 5 of Fig. 3 corresponds to the conductor 5 of Fig. 2 and leads therefore to ground, that is, to the filament circuit. In a similar manner, the output audio frequency transformer 32' has a single primary winding connected serially in the common anode branch of the tubes 17' and 18', the conductor 7 of Fig. 3 leading as in Fig. 2 to the plate battery.

The mode of operation of each of the types of circuit that has been described will be apparent from the detailed description of the circuits already given, and in general will be the same for each of the types shown, except that in the case of Fig. 3, as pointed out above, the tubes 17' and 18' are connected in parallel for the audio waves and not in parallel-opposed or push-pull relation as in the other figures.

It is to be understood that the invention is not to be limited to any particular wave length region nor to any of the values or dimensions that have been given, nor to the specific circuit arrangements that have been described and shown in detail, but only by the scope of the appended claims.

What is claimed is:

1. In a radio receiver, inductance comprising two separate coils, two vacuum tubes each having a grid or impedance control element, an anode and a cathode, said cathodes being in series with each other and with an external heating source; one terminal of each of said coils being connected to a different respective grid, the other terminals of said coils having individual connections to the cathodes of said tubes, a capacity for resonating with said two-coil inductance at the frequency of the waves to be received, and a receiving instrument associated with said anodes.

2. In a radio receiver two wave-intercepting loops, two vacuum tubes each having a cathode, an anode, and a grid or impedance control element, one terminal of each loop being connected to a different respective grid, connections from the other terminals of said loops to earth and to said cathodes, a capacity for resonating with said two loops and a receiving instrument operatively associated with said cathodes and anodes.

3. In a repeating circuit, incoming and outgoing circuits, a repeater stage comprising two vacuum tubes, connected in parallel-opposed relation with respect to said incoming and outgoing circuits, a third vacuum tube connected between said stage and the outgoing circuit, each of said tubes having a cathode adapted to be heated, and a grid, and an anode, a source of cathode-heating current, said cathodes being connected in

- series with one another and said source, a grid-polarizing connection from the grid of one of the parallel-opposed repeaters to one terminal of the cathode of said third vacuum tube, and a grid-polarizing connection from the grid of the other one of the parallel-opposed repeaters to the opposite terminal of the cathode of said third vacuum tube. 5
4. In a repeating circuit, an incoming resonant circuit comprising inductance divided into two portions separated by a capacity, a repeater comprising two vacuum tubes in parallel-opposed relation with respect to said incoming circuit, each tube having a cathode, an anode and a grid, said grids being connected to the respective free terminals of said inductance portions, and separate grid-polarizing connections from the respective terminals of said capacity to the respective cathodes of said vacuum tubes. 10
5. In a radio receiver, an amplifier stage comprising a pair of vacuum tubes connected in balanced relation, another stage working in tandem with the first-mentioned stage comprising a single vacuum tube, each of said tubes having a cathode adapted to be heated, and a grid, a source of current, the cathodes being connected in series with one another and with said source, and connections from each of the grids of said balanced tubes to such points in the cathode-heating circuit that both of said grids have the same normal potential with respect to their respective cathodes. 15
6. In a radio receiver, a wave intercepting circuit, a radio-frequency amplifying stage associated therewith comprising a pair of vacuum tubes each having a cathode, an anode, and a grid, said tubes being connected in balanced relation with respect to the wave-intercepting circuit, an individual inductive winding connected between the cathode and anode of each tube, a second amplifying stage comprising a single vacuum tube having an input winding inductively coupled to said two windings, said two windings having a different number of turns causing unequal coupling with the third winding and establishing two wave repeating paths having substantially different transmission characteristics to enable the transmission of a wider wave-length range than is effectively transmitted between either of the said pair of tubes alone and the third tube. 20
7. In an amplifying circuit, an incoming circuit, an outgoing circuit, receiving means associated with said outgoing circuit, a pair of electron discharge tubes connected in parallel-opposed relation with each other between said incoming and outgoing circuits, each of said tubes having a cathode, an anode and a grid element, said incoming circuit comprising a pair of inductances connected together through two series-connected condensers, a connection from a point in said
- incoming circuit between said condensers to the cathodes of said tubes, a connection from the other terminal of each inductance to a respective grid, individual grid-polarizing conductive connections from the respective grids to the cathodes of said tubes, and a tuning condenser connected across said grids. 70
8. In a radio receiving system, a source of waves, an amplifier for said waves including a plurality of space discharge tubes having respective control electrodes, cathodes and anodes, said cathodes being connected in a series circuit to a source of heating current, input circuits for a plurality of said tubes, including alternating current paths connected to the same point on said series circuit, and direct current conductive paths connected to different points on said circuit. 75
9. A vacuum tube circuit comprising a plurality of tubes arranged in push-pull, each having a cathode and grid, and means for applying to the grid of one of said tubes the potential drop across the cathode of another of said tubes. 80
10. A vacuum tube circuit comprising a plurality of tubes in push-pull relation, each having a cathode and grid, said cathodes being connected in series, and means for applying to the grid of one of said tubes the potential drop across the cathode of another of said tubes. 85
11. A vacuum tube circuit comprising a plurality of tubes in push-pull arrangement, each having a cathode and grid, said cathodes being connected in series with a source of energy, means for applying to the grid of one of said tubes the potential drop across the cathode of another of said tubes, and means for causing the grids of said tubes to have the same biasing potential with reference to their respective cathodes. 90
12. A vacuum tube circuit comprising a plurality of tubes in push-pull arrangement, each having a cathode and grid, said cathodes being serially connected with a source of energy, means for applying equal biasing potentials to the grids of said tubes with reference to their respective cathode, said means comprising connections from said grids to different points on said series circuit. 100
13. A vacuum tube circuit comprising a pair of tubes in push-pull arrangement, each having a cathode and grid, said cathodes being serially connected with a resistance and a source of energy, and means for applying to the grid of one of said tubes the potential drop through the cathode of the other of said tubes, and to the grid of said other tube, the potential drop through said resistance. 110
14. A vacuum tube circuit comprising a pair of tubes in push-pull arrangement, each having a cathode and grid, said cathodes being serially connected with a resistance and 115

- a source of energy, and means for applying equal biasing potentials to the grids of said vacuum tubes with reference to their respective cathodes, said means comprising connections for applying the potential drop through the cathode of one of said tubes to the grid of the other, and the potential drop through said resistance to the grid of said first tube.
- 10 15. A vacuum tube circuit comprising a pair of tubes in push-pull arrangements, each having a cathode and grid, said cathodes being serially connected in a circuit having at least one resistance element and a source of energy, and means for applying a portion of the voltage drop through said series circuit to said grid electrodes to obtain biasing potentials therefor.
- 15 20 25 30 16. A vacuum tube circuit comprising a plurality of tubes in push-pull arrangement, each having a cathode and grid, said cathodes being serially connected in a circuit having a plurality of resistances, and a source of energy, and means for applying the voltage drop through different portions of said series circuit to said grid electrodes to obtain biasing potentials therefor.

In witness whereof, I hereunto subscribe my name this 17 day of December A. D., 1923.
